UNITED STATES PATENT OFFICE.

J ALLINGTON BRIDGMAN, OF OWEGO, NEW YORK, ASSIGNOR TO THE WILBUR WHITE CHEMICAL COMPANY, OF OWEGO, NEW YORK, A CORPORATION OF NEW YORK.

AUTOCLAVE OR THE LIKE.

Application filed April 3, 1924. Serial No. 704,076.

To all whom it may concern:

Be it known that I, J ALLINGTON BRIDGMAN, a citizen of the United States, residing at Owego, in the county of Tioga and State of New York, have invented certain new and useful Improvements in Autoclaves or the like, of which the following is a specification.

The invention relates to autoclaves or similar devices for effecting chemical reactions and the like.

The present improvement comprises in general the construction of the autoclave and the arrangement of the same on the supporting means in such manner that efficient agitation of the contents may be effected, without the necessity of employing a stuffing-box or similar chemically vulnerable packing medium between relatively movable parts of the reaction vessel as heretofore constructed. In the autoclave which forms the subject of this application there are no relatively movable parts in the reaction vessel; no stirring rod, projecting through the end or ends of the autoclave and rotated or reciprocated relatively to the vessel from without the latter, is employed; and the closure for the vessel and the vessel itself turn with the supporting and revolving shaft. The shaft is preferably hollow, communicates directly with the chamber of the autoclave, and is provided with a pressure gage at its upper end, or elsewhere, for indicating the pressure condition in the vessel.

For increasing the agitating effect, the supporting and turning shaft, which lies in a direction axially of the vessel in my device, carries the vessel eccentrically thereof, and furthermore the vessel is preferably supported at an acute angle with the vertical.

The invention will better be understood by reference to the accompanying drawing, wherein:

Fig. 1 is a perspective view of the mounted autoclave from the side;

Fig. 2 is a side view of the autoclave showing a slightly modified manner of mounting, more particularly adapted for larger or commercial application; and

Fig. 3 is a sectional view of the autoclave dismounted from the supporting frame.

The vessel 10, the particular proportions,

material and shape of which are determined of course by the conditions of specific use, is rather conventionally illustrated as a cylindrical chamber with a flat bottom 11 and a substantially flat top 12 and of slightly less diameter than height.

In the form of vessel illustrated, the body of the vessel is provided (see Fig. 3) with a lateral collar 13 and an annular flange 14 which may be integral with the collar 13. The cover 12, shown in the drawing as extending over the entire top of the vessel, has a depending annular rib 15 slightly spaced from the periphery of the cover and which, when the cover is in place, fits snugly within the flange 14. Between the rib 15 and the upper surface of the collar 13 is interposed a gasket 16, and the cover 12, gasket 16 and collar 13 may be perforated for the reception of a number of suitable securing bolts 17, held by nuts 18. The cover may instead be clamped or otherwise suitably secured to the body portion of the autoclave.

Fixed to the cover 12, eccentrically of the latter and therefore eccentrically of the vessel 10, is a tubular shaft 19, the interior of which is in free communication with the reaction chamber through an opening 20 in the cover 12. The tubular shaft 19 may be fixed to the cover in any suitable manner. As illustrated, the cover 12 is formed or provided with an internally threaded boss 21 adapted to receive the externally threaded lower end of the tubular shaft. The shaft 19 need not be very long and may extend only a comparatively short distance from the support above, hereinafter more particularly described. As to the diameter of the shaft and the thickness of its wall, it is only necessary that these be sufficient to enable the shaft to withstand the strains of weight and torque imposed upon it in operation and any pressure to be developed inside the vessel.

The cover 12 may be provided with means for carrying a thermometer 22 or other pyrometric device so that its indicating end will be exposed. As illustrated, the cover 12 has an aperture, the wall of which is threaded and the threads are adapted to receive the threaded neck 23 of a thermometer well 24. The well may have a cap or flange 25 which lies closely against the upper face of the cover 12.

At or near the end of the tubular shaft 19, remote from the reaction vessel, a pulley

26 is pinned or keyed to the shaft and thus provides means for imparting rotary movement from a belt or the like to the shaft. Obviously the pulley may be replaced by a 5 worm, pinion, sprocket or equivalent form of gearing.

A suitable pressure indicator 27 is affixed to the tubular shaft 19, revolves therewith and, communicating with the interior of the 10 shaft, shows the pressure existing in the reaction vessel. The particular location of the juncture of the indicator with the hollow shaft is not important, but preferably the instrument is supported at the end of the 15 shaft so that its dial will lie in the plane of a diameter or of a chord of the shaft. In this position it can more easily be read as the shaft is revolved.

The supporting frame may be of any suitable form. That shown by way of example 20 is somewhat easel-like in general appearance and comprises a pair of fore legs 28 and a pair of rear legs 29 held together in the desired angular relation by means of dowels 25 or the like. The lower ends of the legs may be bent to form feet 31 and the latter may be secured to the floor by bolts or clamps, apertures 32 being shown in the form of Fig. 1 for reception of bolts or screws. 30 The offset upper ends 33 of the rear members 29 are made shorter than the contiguous portions 34 of the front members 28 to accommodate a suitable pillow-block 35, which may be secured to the portions 34 of the 35 front members by bolts 36 or the like. The pillow-block 35 carries a journal-box 37 of any suitable form, providing a bearing for the tubular shaft 19. The box or housing 37 may have the usual lubricant well 38.

40 When a pulley 26 or similar gearing device having sufficient radial surface is employed, the lower side of such device may bear directly against the upper face or end of the journal-box 37 or its bearing; a bearing being thus provided to take the bulk of the weight of the autoclave. Obviously 45 other forms of step-bearings may be substituted for this construction.

The angle of inclination of the shaft 19 and therefore of the autoclave may vary considerably. I have found that such autoclaves having an inclination of between thirty and sixty degrees work very satisfactorily.

50 For ordinary laboratory work and some commercial operations, no support in addition to that heretofore described is required. For larger and heavier work, however, it is desirable to provide an additional point of support to prevent undue wobbling. A second bearing for this purpose is indicated at 40 in Fig. 2. It may be similar in general to the journal-box 37 and may similarly be carried by a pillow-block 41 secured 55 to the fore legs 28. A shaft 42, which may

be solid or hollow, is threaded or otherwise fixed to the bottom of the autoclave and turns in the bearing 40. However, the particular form which this additional bearing support may take is not material.

70 It is believed that the use and operation of the autoclave described will be fully understood without further description. The chemicals may be introduced into and removed from the vessel by removal of the cover 12 from the body portion, or the cover may be provided with a suitable opening having appropriate closing means.

75 It will be seen that by the construction described the necessity for a stuffing-box or similar packing is obviated. This is highly important. Packing, when subjected to the action of chemicals such, for example, as ammonia and alcohol under pressure, never gives particularly good service; and an autoclave having an internal agitator and its requisite stuffing-box is, therefore, a constant source of trouble. There is also danger of blowing out of the packing, resulting not only in serious interruption of the operation 80 and possible loss or destruction of the contents of the autoclave, but also in the escape of fumes which may be of an exceedingly dangerous nature.

85 The device herein described eliminates 90 these objectionable features, and still it provides splendid agitation of the contents of the vessel.

95 The pressure gage revolves with the shaft, but this does not interfere with accurate 100 reading of the gage, since the revolving of the shaft may be comparatively slow. On the other hand, there is a distinct advantage in so mounting the gage for any tendency 105 for the gage to stick or fail to register correctly is overcome by the motion.

110 Certain details not hereinafter specifically claimed are subject of course to rather wide variation without departing from the scope and spirit of the invention.

115 I claim:—

1. In combination, a reaction vessel, means for supporting the vessel in an inclined position, and means for revolving the vessel about an axis parallel to but non-coincident 115 with the axis of the vessel.

2. In combination, a reaction vessel, a rotatable shaft rigidly connected to and supporting said vessel and having its axis parallel to but non-coincident with the axis of 120 said vessel, and means for supporting said shaft in an inclined position.

3. In combination, a reaction vessel, a rotatable shaft rigidly connected to one end of said vessel and supporting the vessel, said shaft having its axis parallel to but non-coincident with the axis of said vessel, and means for supporting said shaft in an inclined position.

125 4. In combination, a reaction vessel hav-

ing a closure adapted to be firmly secured thereto, a rotatable shaft rigidly connected at one end to said closure and thereby supporting said vessel, said shaft having its axis parallel to but non-coincident with the axis of the vessel, and means for supporting said shaft in an inclined position.

5. In combination, a reaction vessel, a rotatable hollow shaft rigidly connected to 10 said vessel and having its interior in communication with the interior of said vessel, said shaft supporting said vessel and having its axis parallel to but non-coincident with the axis of said vessel, a pressure indicating 15 device on the shaft, rotating therewith and communicating with the interior thereof, and means for supporting the shaft in an inclined position.

6. In combination, a reaction vessel having a closure adapted to be firmly secured 20 to the vessel and provided with an opening; a rotatable hollow shaft rigidly connected at one end to said closure over said opening, thereby supporting said vessel and having 25 its interior in communication with the interior of the reaction vessel, said shaft having its axis parallel to but non-coincident with the axis of the vessel; a pressure indicating device on the shaft, rotating there- 30 with and communicating with the interior

thereof, and means for supporting said shaft in an inclined position.

7. In combination, a reaction vessel; a rotatable shaft rigidly connected at one end to said vessel and supporting the vessel, said 35 shaft having its axis parallel to but non-coincident with the axis of the vessel; a journal-bearing above the vessel supporting said shaft in an inclined position; and a gear element above said bearing, fixed to 40 said shaft and forming by lateral contact with the adjacent end of said journal-bearing a step-bearing for the shaft.

8. In combination, a reaction vessel, a rotatable shaft rigidly connected at one end 45 to the top of said vessel and supporting the vessel, said shaft having its axis parallel to but non-coincident with the axis of the vessel; a journal-bearing above the vessel supporting said shaft in an inclined position; a gear element above said bearing, 50 fixed to said shaft and forming by lateral contact with the adjacent end of said journal-bearing a step-bearing for the shaft; a second rotatable shaft in axial alignment 55 with the first shaft and engaging the bottom of said vessel, and a bearing for said second shaft.

In testimony whereof, I affix my signature.
J ALLINGTON BRIDGMAN.
